(57) **CLAIM**

The ornamental design for a sequencer machine, as shown and described.

DESCRIPTION

FIG. 1 is a front perspective view of a sequencer machine, according to a new design;

FIG. 2 is a top back perspective view thereof;

FIG. 3 is a front view of thereof;

FIG. 4 is a left view of thereof;

FIG. 5 is a back view of thereof;

FIG. 6 is a right side view of thereof; and,

FIG. 7 is a top view of thereof.

FIG. 8 is a close-up view of an area of the front of the sequencer machine as indicated by a circle in FIG. 3.

FIG. 9 is a close-up view of the area of the rear of the sequencer machine as indicated by a circle in FIG. 5; and, FIG. 10 is a close-up view of the area of the side of the sequencer machine as indicated by a circle in FIG. 6.

In the drawings, the equal-length broken lines depict portions of the sequencer machine and form no part of the claimed design. The dash-dot-dash broken lines define the limits of the enlarged portions shown. All broken lines form no part of the claim.
